UNITED STATES PATENT OFFICE.

GEORG KÖHLER, DECEASED, LATE OF CASSEL, GERMANY, BY MATHILDE KÖHLER, NÉE BAUCH, WIDOW, AND GUARDIAN OF MINOR CHILDREN FRANZ AND HANS KÖHLER.

RAIL-JOINT.

1,324,906.

Specification of Letters Patent.

Patented Dec. 16, 1919.

Application filed October 16, 1918. Serial No. 258,436.

To all whom it may concern:

Be it known that GEORG KÖHLER, deceased, late a citizen of the Empire of Germany, and resident of Cassel, Germany, has 5 invented certain new and useful Improvements in Rail-Joints, of which the following is a specification.

The present invention has reference to an improved rail joint and relates more 10 specifically to that type of joints in which oppositely disposed fish plates are bracingly interposed between the tread and the base flanges of the abutting rail sections, and the object of the invention is to obviate certain 15 defects attaching to many prior rail joint constructions, by so constructing, arranging and operatively stressing the fish plates that they will not buckle or otherwise be deformed and will, even under the severest 20 strain, always operatively contact over the total area of the respective fishing surfaces.

In order to make the invention more readily understood it will now be described in detail in connection with the accompanying 25 drawings, in which—

Figure 1 represents a vertical cross-section through the improved joint;

Fig. 2 illustrates a perspective side elevation thereof, partly in section, and 30 Fig. 3 is a similar view of a modification.

The rail sections consist of the head or tread portion *a*, the web *b*, and the foot or base portion *c*, and the web is perforated to receive the clamping bolts, all in the well 35 known manner. The fish plates *d* are of approximate U-shape with outwardly flaring flanges *e* and *f* respectively and their webs *g* are drilled in register with the bolt holes in the rail webs. These angle plates 40 closely fit in between the lower bevel face of the rail head and the upper bevel face of the rail foot, making an intimate operative contact all over the respective fishing area, the upper angle plate flanges *e* being corre- 45 spondingly shorter than the lower flanges *f*, as clearly shown in the several figures, in accordance with the extent of the rail flanges. A certain amount of play, as at *x*, must be left between the rail web and the 50 fish plate webs.

Into the U-channel presented by the fish plate is closely fitted a wedge-shaped lock or press plate *h*, with a certain amount of play allowed, as at *y*. This play, as well 55 as the one between the fish plate web and

the rail web, serves for tightening-up purposes. Fish bolts *i* are finally passed through the assembled parts, for operatively clamping them together.

The described construction and connection of parts makes for a very effective joint, inasmuch as the pairs of plates, by their nested arrangement between the rail flanges, very favorably take care of the forces acting on the rails, especially of the 60 vertical stresses, and also for the reason that the web of the angle plates, obviously, cannot be deformed by even the strongest action of the fish bolts. A loosening of the parts, due to wear, need not be feared, nor 65 a break of the angle plate at the notchings *k*, inasmuch as the press plates (Fig. 2) bridge over these notchings.

The improved construction constitutes 70 four-sided rail bracing members, one for each rail side, which when properly interconnected form a joint of high rigidity and able to stand up under the severest strain without appreciable wear.

Instead of employing press plates *h* of 75 even length with the angle plates *d* and passing long bolts *i* through the nested parts, as shown in Fig. 2, there may be used several short press plates *m* for each long angle plate, as shown in Fig. 3, in which 80 case the angle bars are connected to the rail ends intermediate these short press plates by shorter bolts *n*.

What is claimed as new is:—

In a rail joint, in combination with the 90 rail sections, oppositely disposed angle plates of approximate U-shape with outwardly flaring flanges, adapted to closely register in the longitudinal rail channels with a certain amount of play between the 95 rail web and the facing angle plate webs, a plurality of wedge-shaped press plates for each angle bar, spaced apart in the hollow thereof and contacting therewith over practically all of their upper and lower bearing 100 surfaces but with a certain amount of play between the vertical middle portions of the respective plates, means for operatively interconnecting said rail ends, said angle plates, and said press plates, and means in- 105 termediate said press plates for interconnecting solely the rail ends and the angle plates.

MATHILDE KÖHLER, NÉE BAUCH.
Widow of Georg Köhler, deceased.
